CLAIM

The ornamental design for a cup lid assembly as shown and described.

DESCRIPTION

FIG. 1 is a top perspective view of a cup lid assembly showing the stopper separately, to show aspects of the design not visible when combined;

FIG. 2 is a bottom perspective view thereof;

FIG. 3 is a left side view thereof;

FIG. 4 is a right side view thereof;

FIG. 5 is a top view thereof;

FIG. 6 is a top perspective view of the cup lid assembly shown combined with a cup lid;

FIG. 7 is a bottom view thereof;

FIG. 8 is a right side perspective view thereof;

FIG. 9 is a top perspective view of the cup lid assembly;

FIG. 10 is a front perspective view thereof;

FIG. 11 is a rear perspective view thereof;

FIG. 12 is a left side perspective view thereof;

FIG. 13 is a right side perspective view thereof;

FIG. 14 is a top perspective view of a cup lid assembly in an open configuration; and,

FIG. 15 is another top perspective view of a cup lid assembly thereof.

The broken lines shown in the drawings depict portions of a cup lid assembly that form no part of the claimed design.
